(57) **CLAIM**

The ornamental design for a water ski rope tow, as shown and described.

DESCRIPTION

FIG. 1 is a first perspective view of a water ski rope tow showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the detail identified in FIG. 1. The broken lines shown in the drawings depict portions of the water ski rope tow that forms no part of the claimed design.
